UNITED STATES PATENT OFFICE

FRANK W. ANDREWS, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed February 28, 1927. Serial No. 171,485.

This invention relates to refrigerating apparatus in which refrigerant is alternately liquefied and evaporated.

One of the objects is to improve the operation of such apparatus by improving the means for liquefying or condensing the refrigerant.

More specifically it is an object of the invention to provide improved means for cooling the condenser.

Still another object is to provide improved means for supporting the condenser.

Further objects and advantages of the present invention will be apparent from the following description, reference being had to the accompanying drawings, wherein a preferred form of embodiment of the present invention is clearly shown.

Referring to the drawings, Fig. 1 is a perspective view of a condenser embodying the invention.

Fig. 2 is an enlarged section of a portion of the condenser, taken on the line 2-2 of Fig. 1.

Fig. 3 is an end view of a slightly modified form of condenser and

Fig. 4 is a plan view of a portion of a refrigerating machine, showing the condenser coils.

Referring to Fig. 4, a compressor 10, driven by any suitable source of power, not shown, is mounted on a base 11 and draws gaseous refrigerant from an evaporator, not shown, thru a suction conduit 12 and dis-

charges it under pressure to a connection 13 whence it passes to condenser coils 14. These may be for convenience, placed on either side of the compressor. Liquefied refrigerant flows from the condenser coils

at 15 to a suitable evaporator, not shown. A fan 16 is provided for blowing air thru the condenser to cool the latter. This may be mounted on the compressor shaft 17. The fan moves air in the direction of the arrows in Fig. 4, and the coils are placed with

their convolutions lying substantially in planes parallel to the direction of the air currents.

The condensers are formed by winding a continuous strip of metal tubing 20 into

a helical coil on a suitable form. The tubing may be either flat, as in Figs. 1 and 2, or round as shown in Fig. 3. It has been found that when such a coil is removed from the form, the convolutions unwind somewhat, due to the elasticity of the tubing. To prevent such unwinding, the convolutions are held in place by clamping members 21 and 22, arranged in pairs and held together by bolts 23. Preferably three pairs of such clamps are arranged on the coils as shown in Figs. 1 and 4.

In order to hold the convolutions suitably spaced along the clamps, I place between the coil and one of each of the pairs of clamps a serpentine strip of sheet metal 24. The individual convolutions are clamped firmly in the depressions 25 and are held in close thermal contact with the strip 24 by the bolts 23. The strip 24 is preferably made of some good thermal conductor, such as copper, and due to the elevated portions 26, forms fins for the transfer of heat from the tubing to the air currents.

The fins are placed with their flat sides parallel to the direction of the air currents in order to leave unobstructed passage for air between the clamps along the convolutions.

Preferably the portions 26 are spaced between the clamps 21 and 22 as shown in Fig. 2, to provide air passages 27 and 28 on either side. This arrangement exposes the maximum surface to the air currents.

In order to support the coil on the machine base 11 or in other positions, I bend the ends of the clamping members 21 at right angles to form the supports 29, which may be provided with bolt holes 30. The coil may be placed vertically as in Fig. 4, or in any other position such as horizontally, as in Figs. 1 and 3.

While the form of embodiment of the present invention as herein disclosed, constitutes a preferred form, it is to be understood that other forms might be adopted, all coming within the scope of the claims which follow.

What is claimed is as follows:

1. Means for supporting condenser coils comprising a pair of clamping members between which the coil is adapted to be held, and a thermally conducting member between the clamping members, said conducting member having recesses for holding the convolutions of a coil in place. 70
2. In a support for condenser coils comprising a pair of means between which a coil is adapted to be clamped, a sheet metal strip adapted to be clamped between one of said means and a coil and having undulations for spacing the convolutions of a coil. 75
3. A condenser adapted to be cooled by air currents comprising in combination a coil of tubing, a pair of clamping means for securing the convolutions of the coil in place, and spacing means between the clamping means and between said convolutions, said spacing means permitting unobstructed passage of air along the convolutions between the clamping means. 80
4. A condenser adapted to be cooled by air currents comprising in combination a coil of tubing a pair of clamping means for securing the convolutions of the coil in place, and spacing means between the convolutions comprising heat conducting means in thermal contact with the coil. 85
5. A condenser adapted to be cooled by air currents comprising in combination a coil of tubing, a pair of clamping means for securing the convolutions of the coil in place and spacing means between the convolutions comprising heat conducting fins in thermal contact with the coil, said fins being arranged to provide unobstructed air passages between the clamping means along the convolutions. 90
6. Refrigerating apparatus comprising in combination, means for moving air, means for condensing refrigerant including a coil of tubing having its convolutions substantially parallel to the direction of motion of the air, clamping means for supporting the convolutions of the coil, and spacing means for the convolutions comprising heat conducting fins disposed parallel to the direction of motion of the air. 95
7. Refrigerating apparatus comprising in combination, means for moving air, means for condensing refrigerant including a coil of tubing having its convolutions substantially parallel to the direction of motion of the air a pair of clamping means for supporting the convolutions of the coil, and spacing means for the convolutions comprising heat conducting fins disposed parallel to the direction of motion of the air. 100
8. A tube coil having a support comprising a pair of clamping members between which the coil is adapted to be held, and a thermally conducting member between the clamping members, said conducting member having recesses for holding the convolutions of a coil in place. 105
9. A tube coil having a support comprising a pair of means between which the coil is adapted to be clamped, a sheet metal strip adapted to be clamped between one of said means and the coil and having undulations for spacing the convolutions of the coil. 110
10. A tube coil adapted to be subjected to fluid currents comprising in combination a coil of tubing, a pair of clamping means for securing the convolutions of the coil in place, and spacing means between the clamping means and between said convolutions, said spacing means permitting unobstructed passage of fluid along the convolutions between the clamping means. 115
11. A coil to be subjected to fluid currents having a pair of clamping means for securing the convolutions of the coil in place, and spacing means between the convolutions comprising heat conducting means in thermal contact with the coil. 120
12. A coil adapted to be subjected to fluid currents having a pair of clamping means for securing the convolutions of the coil in place and spacing means between the convolutions comprising heat conducting fins in thermal contact with the coil, said fins being arranged to provide unobstructed fluid passages between the clamping means along the convolutions. 125

In testimony whereof I hereto affix my signature.

FRANK W. ANDREWS.
